UNITED STATES PATENT OFFICE.

STEPHEN F. TOJEK, OF MILWAUKEE, WISCONSIN, ASSIGNEE TO STEPHEN F. TOJEK AND PHILIP TOJEK, COPARTNERS DOING BUSINESS UNDER THE FIRM NAME AND STYLE OF TOJEK BROTHERS, OF MILWAUKEE, WISCONSIN.

FEEDING DEVICE FOR SHAPING PRESSES.

Application filed August 2, 1926. Serial No. 126,430.

My invention relates to improvements in feeding devices for shaping presses, of that class in which a plurality of thin disks or blanks of paper or similar material are to be delivered from the bottom of a pile or stack to a shaping press having a die in which the superposed blanks may be simultaneously shaped by a single operation of the press plunger.

6

10 The object of this invention is to provide improved means for feeding the blanks from the bottom of the pile to the press in synchronism with the movements of the press plunger.

15 There are two stages of the blank feeding operation, i. e., the separating stage, which involves a separation of a desired number or bundle of blanks from the bottom of the pile in the magazine and the feeding stage which involves a delivery of the separated blanks from a lower or base portion of the magazine to the press. The separation of the blanks is accomplished by a set of blades carried by a slide similar 20 to that disclosed in Letters Patent to H. C. Harvey, No. 1,238,138, dated August 28, 1917.

25 Specifically stated, the primary object of this invention is to provide means whereby the press will automatically actuate and control the separator blades to deliver a bundle of blanks into the path of a feed block or follower which is then also automatically actuated to deliver the blanks to 30 the press in a quick initial movement, followed by a progressive retardation and substantially a final dwell as the blanks are positioned upon the die, the follower being then retracted by a spring and with a quick 35 throw, in time for the next blank separating stage of the feeding operation. This enables me to operate the press and feeder at a high rate of speed, the only retarded movement being that required for accurate- 40 ly positioning the blanks on the die.

45 Another object of this invention is to provide a feeder which is adjustable for feeding blanks of different sizes.

In the drawings:

50 Figure 1 is a front elevation of a machine embodying my invention, the machine

illustrated being used in the manufacture of paper cups, and portions of the feeding mechanism and magazine being broken away or illustrated in vertical section.

55

Figure 2 is a plan view of the base portion of the magazine, showing the separator blades and slide, with associated parts, the magazine posts being shown in cross section.

60

Figure 3 is a side elevation of the machine as viewed from the right-hand side in Figure 1.

Figure 4 is a plan view of the feeding mechanism.

65

Like parts are identified by the same reference characters throughout the several views.

The general organization of the press forms no part of my invention and is therefore briefly referred to only in so far as appears necessary to clarify the description of the feeder and its relation to and control by the press.

70

As best shown in Figure 2, the plunger 75 10 of the press is operated from a cross head 11, which is guided by the vertical posts 12 and actuated from the overhead shaft 13 through crank 14, connecting rod 15 (Figure 1) and vertically movable slide 16, to the 80 lower margin of which the cross head 11 is connected. The co-operating relatively stationary die member 17 is mounted upon the table 18. When the movable die or plunger 10 is raised, the paper blanks are fed 85 into position on the die member 17 and the latter depressed in the form by pressure of the die 10 thereon. The dies are illustrated conventionally, and it is to be understood that a variety of dies of differing sizes and 90 shapes may be used interchangeably.

95 The paper blanks are stored in the form of a pile of superposed blanks in a magazine composed of a set of vertical rods 25 socketed in the bottom plate 26 of the magazine or feeder base, which is mounted on the table 18. These blanks are normally supported on a blade 27 which is adjustably secured to a slide 28 by bolts 29, which pass through slots 30 in the blade, as clearly shown in Figure 2. The slide 28 is mounted for horizontal movement in suitable guideways 31 formed on the

100

base plate 26. By retracting this slide (to the right in Figure 2), the blade 27 may be withdrawn from beneath the pile of blanks, and the blanks will thus be allowed to drop upon another blade 35 similarly secured by bolts 29 to the opposite end of the same slide, but at a lower level. The blades 27 and 35 lie in horizontal planes, which are separated vertically to an extent corresponding with the height of the bundle of superposed blanks to be fed to the press by a single feeding operation. Therefore, when the pile of blanks in the magazine has been allowed to descend by gravity to the blade 35, a return movement of the slide 28 will cause the point 27' of the blade 27 to enter the pile of blanks at the desired height above its bottom to separate those blanks below this blade 27 from those above it. Simultaneously with this separating movement of the blade 27, the blade 35 will be withdrawn, whereupon the separated blanks will be permitted to drop into a feedway 37 formed by the plate 26, and a set of adjustable side wall members and which feedway extends rearwardly to guide the blanks to the die 17.

The blanks are pushed along this feedway 37 by a follower or pusher block 38, which is provided with an actuating arm 39 extending downwardly through a slot in the plate 26 and table 18 and connected with the elbowed slide bar 40. The side walls 41 and 42 of the feedway are adjustable to increase or diminish the width of the guideway in accordance with the size of the blanks which are being fed. Each wall comprises a flanged portion of a plate 44 having laterally extending slots through which bolts 45 may pass to secure these plates 44 to the plate 26.

The slide 28 is similar to that shown in said patent to Harvey. Also the separating blades 27 and 35, the actuating crank arm 50 and associated latch bar 51, with the headed catch pin 53 on the blade carrying slide, the latch operating spring 54, the oblique throw-out arm 55, abutment pin 56, slide retracting weight 57 and associated cable 58, are substantially as disclosed in said patent and require no further description. But in my improved structure the crank arm 50 is connected with the latch bar 51 by a stud 65 adjustably engaged in the longitudinally extending crank slot 66 whereby the stroke 55 of the slide may be varied in accordance with the size of the blanks to be fed. This crank arm 50 is actuated from the vertical feeder shaft 67 through the disk 68, crank pin 69, connecting link 70, slotted crank 71 and vertical shaft 72, the link bar 70 being adjustably pivoted in the slot of crank 71 by a pivot bolt 73.

The feed block or follower 38 will also be reciprocated along the feedway by power derived from the vertical shaft 67, this shaft

being driven from the shaft 13 through the bevel gears 75 and 76. The connections for transmitting motion from this shaft to the feed block or follower 38 will not be described.

70

To actuate the feed block or follower 38 for feeding the separated blanks to the dies of the press the shaft 67 is provided with a cam 80 having a bearing surface 81 adapted to engage a roller 82 on a stud 83 mounted on a lever 84 connected with the under surface of the table by a fulcrum pin 85. This lever 84 is normally held in the position in which it is illustrated by full lines in Figure 4, by means of a spring 86, which connects it with the table at 87, but when the lever is swung from this position by the pressure of the cam 80 against the stud roller 82, motion is transmitted to the feed block or follower 38 through the link 90, lever 91, and link 92, the latter being pivotally connected to the elbowed slide bar 40. This motion will continue until the lever 91 has been swung to the position in which it is indicated by dotted lines in Figure 4. The bearing surface 81 of the cam will be so contoured that the final movement of the lever 91 and the associated follower 38 will be relatively slow as the portion 93 of the cam passes the roller 82. At this time the blanks will be placed by the follower in position on the die 17. There will then be a slight dwell in the movement of the follower until the end of the cam passes the roller 82, whereupon the spring 86 will instantly restore the levers 84 and 91 to their normal position with the feed block or follower 38 retracted.

130

When the lever 91 is in the dotted line position of Figure 4, the feed block will have moved inwardly or rearwardly and will have carried the separated pile of blanks to a superposed position on the die member 17. The inner face of the follower is concavely curved in substantial conformity to the peripheral contour of the blanks. When blanks of different diameters are to be fed, the side walls of the slideway are correspondingly adjusted as above explained, and a follower 38 of appropriate size will, of course, be substituted for the one shown in the drawings, and in order that the range of movement of the follower may be varied to correspond with variations in the diameters of the blanks that are being fed, the lever 91 is formed in overlapping sections, one of which is longitudinally slotted and connected to the other by set screws 94. By adjusting these sections upon each other and securing them together by the set screws 94 in their newly adjusted positions, the stroke of the follower may be varied in proportion to the increased or diminished length of the lever 91.

The position of the cam 80 on the shaft 67 is such that it will not actuate the lever 84

130

and its associated connections with the follower 38 until after the separator slide has been released from the latch bar 51 and retracted by the weight 57 to deliver the separated bundle of blanks into the feedway. But when this has been accomplished, the cam 80 will actuate the follower with a quick but controlled stroke, the movement of the cam actuated stud 83 being multiplied in the compound lever mechanism above described. But as the blanks approach the receiving die 17, the motion of the follower is progressively retarded after the cam bearing point 93 reaches the stud roller 82, and the contour of the end of the cam is such that the final movement of the follower is scarcely perceptible, there being substantially a dwell just before the end of the cam clears the roller 82. Thereupon the abrupt face 96 of the cam allows a substantially instantaneous retraction of the follower under the recoil of the spring 86.

I claim:

1. In a shaping press for blanks of paper and similar material, said press having a driven rotary shaft, the combination of a magazine for the blanks, means operated from said shaft for separating bundles of superposed blanks from those in the magazine, a reciprocating feeding device for delivering the bundles of blanks successively to the press, compound lever mechanism for actuating said feeding device, and a cam on said rotary shaft adapted to actuate the power arm of said compound lever mechanism once during each turn of the shaft.

2. The combination with a rotary driven shaft, of a drawing press, of a magazine adapted to receive a pile of superposed blanks to be fed to said press, a cam on said shaft, an associated lever provided with a bearing to be engaged by said cam once during each revolution of the shaft to actuate said lever, compound lever mechanism for multiplying the movement imparted by said cam, a feeding slide for delivering blanks from said magazine, and link connections between said feeding slide and the driven member of said compound mechanism.

3. In a shaping press, the combination of a pivoted lever provided with a laterally projecting stud, a press operated rotary cam

adapted to transmit motion to the lever through said stud, a reciprocating feed slide for delivering material to the press, and motion amplifying connections for transmitting movement from said lever to the feed slide.

4. The combination with the stationary die of a shaping press, of a feed table, a magazine having a base portion mounted on said table and provided with a slideway, the walls of which are adjustable to increase or diminish the width of the slideway, means for successively delivering bundles of blanks from the upper portion of the magazine to said slideway, a follower reciprocable in said slideway to deliver said bundles of blanks to the press, and press actuated means for reciprocating said follower in timed relation to the movements of the press and the bundle separating devices.

5. The combination with the stationary die of a shaping press, of a feed table, a magazine having a base portion mounted on said table and provided with a slideway, the walls of which are adjustable to increase or diminish the width of the slideway, means for successively delivering bundles of blanks from the upper portion of the magazine to said slideway, a follower reciprocable in said slideway to deliver said bundles of blanks to the press, press actuated means for reciprocating said follower in timed relation to the movements of the press and the bundle separating devices, said press actuated means including a compound lever mechanism linked to the follower and press actuated cam for moving the lever mechanism in one direction, and a spring for retracting said mechanism when released by the cam.

6. The combination with a shaping press, of an expandible magazine for storing blanks to be fed to the press for shaping operations, an expandible slideway adapted to receive the blanks from the storage portion of the magazine, press controlled means for delivering bundles of blanks from the magazine to the slideway and subsequently delivering them to the press in timed relation to the movements of the press, and independent means for retracting the blank separating and delivering mechanisms.

STEPHEN F. TOJEK.
